UNITED STATES PATENT OFFICE.

FERDINAND BURCHARTZ, OF NEW YORK, N. Y.

BUILDING-BLOCK.

1,047,614.

Specification of Letters Patent. Patented Dec. 17, 1912.

Application filed November 17, 1910. Serial No. 592,824.

To all whom it may concern:

Be it known that I, FERDINAND BURCHARTZ, a citizen of the United States, and resident of the borough of Manhattan, city, county, and State of New York, have invented certain new and useful Improvements in Building-Blocks, of which the following is a specification.

My invention relates to blocks such as are used in buildings, particularly for the construction of floors and ceilings, and has for its object to provide a novel sectional block which will be readily manufactured, light in weight, fire-proof, and a good heat-insulator.

Various forms of my invention are illustrated in the accompanying drawings, in which—

Figure 1 is a plan view showing a portion of a floor made with square blocks embodying my invention; Fig. 2 is a perspective view of two sections forming a block such as represented in Fig. 1, said sections being shown separated; Fig. 3 is a perspective view, similar to Fig. 2, showing another way of constructing square blocks according to my invention; and Fig. 4 is a plan view of a hexagonal block embodying my invention.

In each of the forms shown, the block comprises two like hollow sections each having parallel main surfaces, adapted to form the top and bottom surfaces of the block respectively when the blocks are used to construct a floor or ceiling. Each block is of polygonal shape, and the open meeting surfaces of companion sections are disposed diametrically with respect to the polygonal outline of the block, and preferably, as shown, such meeting surfaces are in planes perpendicular to the parallel surfaces above mentioned.

Turning more specially to the blocks illustrated by Figs. 1 and 2, I have shown each block section shaped substantially as a hollow triangular prism having a horizontal top surface A, a bottom surface A' parallel thereto, converging vertical side walls A², and an open vertical surface A³ which extends between the ends of the side walls and which I term a meeting surface since it is adapted to fit against the corresponding surface of a companion section to form a block of square outline, as shown in Fig. 1. Each block section is hollow and open at the meet-

ing surface A³ but closed otherwise. When two companion sections are fitted together, they form a hollow block the walls of which are closed entirely. The meeting surfaces A³ are vertical, that is, perpendicular to the parallel surfaces A, A', and in the assembled block the meeting surfaces (indicated by the lines a in Fig. 1) are disposed diametrically with respect to the polygonal (square) outline of the block.

I prefer to make the block sections with flanges A⁴ extending at the bottom beyond the side walls A² and adapted to abut against the corresponding flanges of adjacent blocks, as shown in Fig. 1, thus leaving spaces between the side walls A² of adjoining blocks, to receive the customary supporting rods (two of which are indicated at D) and the cement filling (not shown) in which they are embedded as usual. Of course the improved blocks may be applied in other ways, and I have used the terms top and bottom, horizontal and vertical, only for the sake of convenience of description, since it will be obvious that the blocks might be used in other positions.

The block illustrated in Fig. 3 differs from that shown in Figs. 1 and 2 only by the fact that the diametral meeting surfaces B³ are parallel to one set of side walls B², instead of being arranged diagonally as in Figs. 1 and 2. The outline of each block section is therefore rectangular instead of triangular.

Fig. 3 represents a hexagonal block embodying my invention. Each section is trapezoidal in outline, with the open meeting surfaces (indicated at c) arranged in a diagonal. It will be understood that in other respects the forms shown in Figs. 3 and 4 agree with the one shown in Figs. 1 and 2, hence further description is deemed unnecessary, corresponding parts being designated by reference letters bearing like indices.

The block sections herein described are made by molding or otherwise from cement or other suitable material.

I claim as my invention:

A completely closed hollow sectional polygonal building block having a single inner chamber occupying the whole interior thereof and composed of two similar hollow half sections comprising respectively integral top, bottom and angled side walls, said sections

opening into each other diametrically from end to end thereof and being provided respectively along their said angled side walls with integral angled outward spacing flanges which together form a continuous flange surrounding the block.

In testimony whereof I have signed this

specification in the presence of two subscribing witnesses.

FERDINAND BURCHARTZ.
